US0D1023582S

(12) **United States Design Patent** (10) **Patent No.:** **US D1,023,582 S**
(45) **Date of Patent:** **** Apr. 23, 2024**

(54) **TOOTHBRUSH**

(71) Applicant: **Colgate-Palmolive Company**, New York, NY (US)

(72) Inventors: **Fan Gang Xie**, Shanghai (CN); **Wen Jin Xi**, Shanghai (CN); **Yanmei Ji**, Jiangsu (CN); **Jiang Zhou**, Yangzhou (CN); **Douglas Hohlbein**, Hopewell, NJ (US)

(73) Assignee: **Colgate-Palmolive Company**, New York, NY (US)

(**) Term: **15 Years**

(21) Appl. No.: **29/825,013**

(22) Filed: **Jan. 28, 2022**

Related U.S. Application Data

(62) Division of application No. 29/728,929, filed on Mar. 23, 2020, now Pat. No. Des. 943,283, which is a division of application No. 29/673,234, filed on Dec. 13, 2018, now Pat. No. Des. 883,677.
